UNITED STATES PATENT OFFICE.

WILLIAM H. GAY, OF PORTLAND, MAINE, ASSIGNOR TO EDWARD T. BURROWES, OF SAME PLACE.

DESIGN FOR A SKATE-STRAP.

SPECIFICATION forming part of Design No. 34,115, dated February 19, 1901.

Application filed January 23, 1901. Serial No. 44,477. Term of patent 14 years.

To all whom it may concern:

Be it known that I, WILLIAM H. GAY, a citizen of the United States, residing at Portland, in the county of Cumberland and State of Maine, have invented and produced a new and original Design for Skate-Straps; and I do hereby declare the following to be a full, clear, and exact description of the same, reference being had to the accompanying drawings, forming a part thereof.

This invention relates to an original design for skate-straps; and it consists in the particular shape of the strap presently to be described, and shown in the accompanying drawings.

In the accompanying drawings, Figure 1 is an elevation of a strap embodying the design, and Fig. 2 is an edge view thereof.

The design consists, essentially, of a narrow portion A, which at one end is extended

transversely into a widened oval portion B, which latter portion terminates in a reduced tag portion C, carrying a fastener D. The widened portion of the strap is bulged in opposite directions, as shown in Fig. 2. 25

The essential feature of the design is the strap having the widened bulged portion with the tag at the end, substantially as shown.

Having thus described the invention, what is claimed as new, and desired to be secured by Letters Patent, is— 30

The design for a skate-strap substantially as shown and described.

In testimony whereof I affix my signature in presence of two witnesses.

WILLIAM H. GAY.

Witnesses:
